UNITED STATES PATENT OFFICE.

SYLVESTER LEO GOOKIN, OF BOSTON, MASSACHUSETTS, ASSIGNOR TO UNITED SHOE MACHINERY CORPORATION, OF PATERSON, NEW JERSEY, A CORPORATION OF NEW JERSEY.

FASTENER-SETTING MACHINE.

1,371,364.

Specification of Letters Patent. Patented Mar. 15, 1921.

Application filed June 15, 1918. Serial No. 240,202.

To all whom it may concern:

Be it known that I, SYLVESTER L. GOOKIN, a citizen of the United States, residing at Boston, in the county of Suffolk and State 5 of Massachusetts, have invented certain Improvements in Fastener-Setting Machines, of which the following description, in connection with the accompanying drawings, is a specification, like reference characters 10 on the drawings indicating like parts in the several figures.

This invention relates to fastener setting machines and is herein shown as embodied in a machine particularly designed for setting compound or two-part fasteners but is not limited to use in such a machine.

In certain classes of work, notably in certain types of shoes and other articles of clothing which are designed to withstand 20 rough usage, it is found that single eyelets for lacing holes are not wholly satisfactory because there is a likelihood that the eyelets will be loosened or even pulled out so as to leave the holes unprotected. Machines 25 have, therefore, been designed for setting eyelets or gromets and washers disposed upon opposite faces of the work and intended to eliminate this difficulty. Serious difficulties have attended this kind of work as 30 heretofore practised and special and expensive machinery is required for speedily and accurately carrying out the setting operation.

It has been proposed to avoid these difficulties by setting a row of single eyelets from one side of the work and then setting smaller eyelets from the opposite side of the work in telescopic relation with those of the first set. Obviously, however, this involves 35 two operations and the danger of imperfect alinement between the two sets of fasteners.

An object of the present invention is to provide an improved machine for setting 40 both parts of a two-part fastener in one operation, whether the fastener comprises two telescopic eyelets or a gromet and washer, although, for purposes of illustration a machine for setting telescopic eyelets has been 45 selected. It will be understood, however, that in referring to telescopic eyelets many considerations apply also to a gromet and washer couple, and that the latter is to be inferred whenever and wherever the facts 50 permit, without specific mention of such couple in every case.

In machines for setting gromets and washers it has been found desirable to provide means for centering the washer upon the spindle of the set that presents it to the 55 work, and, as this spindle must necessarily be of small enough dimensions to enable it to pass through the barrel of the co-operating gromet or eyelet, it follows that the washer will be loose relatively to the spindle, and some difficulty has therefore been 60 experienced in preventing interference between the end of the eyelet barrel and the inner edge of the washer. In assembling two eyelets in telescopic relation the same 65 difficulty has been found, namely, that of preventing interference between the barrel of the smaller eyelet and the barrel of the larger eyelet.

Another important feature of the invention, therefore, consists in improved means 70 for presenting and guiding eyelets into telescopic relation in the work. Accordingly the means for this purpose, as shown, is such that coaxial relation of the eyelets is insured 75 when the smaller eyelet is about to enter the larger eyelet. In the preferred embodiment, the larger or reinforcing eyelet is presented to the lower side of the work by a setting tool that has a concentric pilot formed 80 integrally therewith. This pilot is preferably tapered and is so long that its leading end will pass completely through and beyond the work to receive the end of the barrel of the smaller eyelet and to guide it through 85 the hole in the work and into the barrel of the larger or reinforcing eyelet. For the purpose of this application, the larger eyelet is called the "reinforcing eyelet" because it takes the place of a washer, and, in the 90 novel arrangement herein described, it may or may not be clenched upon the work. Preferably the barrel of the smaller eyelet is initially contracted or tapered at its free 95 end. Two uses are made of this feature, to wit, the eyelet is first frictionally supported above the work by clinging engagement with the compressible spindle of the top set, and, as the eyelet is forced downwardly by the upper setting tool, it is held seated 100 against the tool by its gripping effect on the tapering pilot of the bottom set as it is guided by the pilot into the work and into 105

the barrel of the larger eyelet. It will be seen that, owing to the tapering of the pilot on the lower set, the leading end of the barrel of the smaller eyelet is gradually stretched as it progresses along the pilot and the initial contraction of the leading end is wholly eliminated before the latter reaches the clenching surface at the base of the pilot. In the setting operation, as the two eyelets 10 are substantially simultaneously presented to opposite sides of the work, the barrel of the larger eyelet will be supported by the tapered pilot until it engages and is guided upon the outside of the barrel of the smaller eyelet in the passage through the work. The pilot preferably tapers faster than the barrel of the reinforcing eyelet does so that a space is insured between the two for the ready admission of the barrel of the smaller 20 eyelet.

It will be noted that in case there is a variation in the thickness of the work or in case the setting tools are not properly adjusted in the machine, there is no possibility 25 of a buckling of the barrel of the smaller eyelet because it is supported from within by the tapered pilot of the bottom set and from without by the barrel of the larger eyelet. The maximum holding effect of the eyelets 30 may be obtained when the barrel of the larger eyelet is long enough to be clenched against the work by engagement with the flange of the smaller eyelet as the latter is supported by the top set, but it is not altogether necessary that the larger eyelet should be clenched upon the work since it 35 will be tightly anchored by the clenching of the barrel of the smaller eyelet in engagement with its flange.

40 It will be seen that the upset end of the inner eyelet is necessarily exposed and when it is arranged upon the inside of the shoe, for example, it is desirable to make it as smooth as possible in order to avoid chafing 45 the foot of the wearer. To this end it has been proposed to roll the upset end of the barrel, but heretofore, so far as I am aware, this rolled end has projected beyond the plane of the surrounding flange of the 50 washer or eyelet, as the case might be.

For the purpose of avoiding such projecting relation another feature of the invention consists in a setting tool having an upsetting surface disposed above the plane of the 55 seat that supports the flange of the larger eyelet. In order to obtain the greatest advantage from this feature the barrel of the outer or reinforcing eyelet is preferably flared adjacent to the point where the flange 60 joins it and the leading end of the inner eyelet is turned back and clenched in the space so provided in the barrel of the reinforcing eyelet.

65 The invention is illustrated as embodied in a machine of the type set forth in Letters

Patent of the United States No. 934,066, granted September 14, 1909, upon an application of George Goddu, although the invention is not restricted to such embodiment.

Other features of the invention will appear from an inspection of the accompanying drawings taken in connection with the following specification. In the drawings,—

Figure 1 is an angular view of a machine constructed in accordance with this invention;

Fig. 2 is an elevation partly in section of the operating tools disposed in the positions which they occupy when the machine is at rest and viewed from the opposite side of 80 the machine;

Fig. 3 is a similar view showing the punch and punching block in coöperating relation to make an aperture in the work;

Figs. 4 and 5 are similar views showing 85 successive positions of the setting tools;

Figs. 6 and 7 are enlarged sectional views showing the relative positions of the setting tools as the eyelets begin to telescope and the final setting position of the tools; and 90

Figs. 8 and 9 are enlarged fragmentary views of the sides of the hopper.

Reference is made to the Goddu Patent No. 934,066 above mentioned, for a more complete description of parts of the machine 95 not herein fully described. Such a machine comprises a pivoted U-shaped frame 10 whose arms are provided with bearings for the coöperating oppositely disposed tools. Striking members 12 are supported upon 100 levers 14 pivoted in a frame 16 and are arranged to strike against the outer ends of the coöperating tools to bring them toward one another and into operative relation with the work. The retraction of the coöperating tools may be conveniently accomplished by means of a spring actuated lever 18 which may be constructed in accordance with the arrangement described in Letters Patent of the United States No. 1,122,310, 110 granted December 29, 1914, upon an application of Fred A. Rumney. The work may be supported between the tools by a rigid plate 20 bearing against the top side of which is a spring pressed foot 22 of well known construction. An edge gage 24 is provided in connection with the plate 20.

The punching of the work may be effected by means of coöperating tools 30 and 32 of which the former is a tubular punching 120 member having its exterior slightly tapered and the coöperating member 32 is a punch block adapted to support the work against the action of the tubular cutting punch 30. It will be noted that with this preferred 125 arrangement of the punch below the work, the cuttings or pills will pass downwardly through the bore of the punch and drop out below the level of the work. By reason of this arrangement, there is no possibility that 130

these punchings will get caught between the operating tools or the fasteners and the work. Furthermore, the tapered exterior of the punch slightly enlarges the size of the hole at the lower face of the work and thereby makes it more perfectly adapted for the reception of the barrel of the larger eyelet which will be presented thereto by the lower set in a manner to be later described. From 5 an inspection of Fig. 3 it will be seen that the punch block is arranged to move to a position just at the top face of the work as the latter is supported by the plate 20 and the said work plate, being close beside the tubular punch, helps to strip the work therefrom in case there is any sticking of the punch in the work as the punch recedes.

The lower setting tool 40 is provided with a fixed and preferably integral tapered pilot 20 and surrounding this pilot is an annular upsetting surface 44 slightly raised above the general level of the face of the tool 40 and designed to upset the barrel of the smaller eyelet which is guided thereagainst 25 by the pilot 42. Surrounding this upsetting surface 44 is an annular concentric seat 46 which is adapted to receive and to support the flange of the larger reinforcing eyelet as it is presented to the work by the tool 30 40. It will be noticed that the general level of this seat 46 is slightly below the level of the groove 44 so that the upset end of the barrel of the smaller eyelet (see Fig. 7) is slightly within the level of the outside of 35 the embossed flange of the larger eyelet when applied to the work. The upper setting tool 50 is maintained in alignment with the tool 40 by the frame 10 in the usual fashion and is provided with a spring expelled depressible spindle 52 having its outer end slightly tapered at 54 and provided with a conical recess 56 to receive the point of the pilot 42. Surrounding this spindle is an annular groove 58 adapted to support the 40 45 flange of the smaller and upper eyelet as the eyelets are brought into telescoping relation in the work and are secured therein by the action of the setting tools.

Eyelets of different sizes, that is to say, 50 having barrels of different sizes, are then applied to the respective setting tools by means of raceways 60 and 62 of usual and ordinary construction which are supplied from a hopper 64. This hopper is adapted to be filled with an indiscriminate mass of eyelets of different sizes or characters and is provided with the usual series of ports 55 adjacent to its lower edge upon the two sides to permit the outward passage into the raceways of properly disposed eyelets. It will be noted, however, that the ports 66 leading to the lower raceway 62 are lower and broader (see Fig. 9) than are the ports 68 (see Fig. 8) upon the opposite side of the 60 65 hopper and communicating with the upper

raceway 60. From an inspection of Figs. 8 and 9 it will be seen that eyelets 70, which it is desired to deliver to the upper raceway, are provided with relatively long and narrow barrels whose outer ends are flared inwardly 70 while the eyelets 72, which it is desired to deliver to the lower raceway, are provided with relatively short broad barrels whose outer ends are substantially cylindrical, *i. e.* with parallel sides. By reason, therefore, 75 of the arrangement of the ports of the hopper, only one type of fastener can pass into either of the raceways and even though the fasteners become nested, as shown in Fig. 9, they cannot pass out into either of the raceways. The usual agitator 74 serves constantly to stir up the mass of eyelets in the hopper and tends to disengage those eyelets 80 which have become nested.

The general operation of the parts of the 85 machine is very similar to the operation of the corresponding parts of the machine shown in the Goddu patent. A piece of work 76 having been inserted between the presser foot 22 and the work plate 20 and 90 against the edge gage 24, the punching tools come together at a predetermined point and make a hole in the work and then, because of a movement of the U-shaped frame 20, move out of alignment with said hole and 95 bring the oppositely disposed setting tools into alignment therewith. The ends of the raceways then move into alignment with said tools to allow the threading of the endmost fasteners therein by the spindle and 100 pilot respectively of the upper and lower tools and move again out of alignment with the tools leaving the eyelets upon said spindle and pilot respectively. In applicant's novel arrangement, however, the eyelets delivered to the lower tool are provided 105 with a relatively short, broad barrel while those delivered to the upper tool are provided with a relatively narrow, long barrel. Preferably the eyelets delivered to the upper 110 tool have the outer ends of their barrels flared inwardly and are frictionally engaged by the slightly tapered lower end of the de-pressible spindle 52 of the top set. Because 115 of the angular position of the setting tools, a fastener delivered to the lower tool will hang loosely upon the fixed pilot 42 and for the purpose of the present invention must necessarily have an internal diameter which exceeds the greatest external diameter of the 120 fixed pilot 42 by an amount equal to the thickness of the barrel of the smaller eyelet. Because the pilot tapers faster than the barrel of the larger eyelet does, there will always be a space between the end of this 125 barrel and the pilot even though the tools are arranged in an angular position, as shown. As the setting tools 40 and 50 are brought together on opposite sides of the piece of work, the spindle 52 of the top set 130

will meet the pilot 42 of the bottom set at approximately the level of the work and will be forthwith pushed back into the top set as the two tools are still further brought 5 together. During this time the outer and upper end of the fixed pilot 42 will have completely traversed the aperture in the work and, as it depresses the spindle 52, will release the smaller eyelet from frictional engagement with the spindle at the top set and allow the same to drop into engagement with the upper end of the fixed pilot. The continued approach of the setting tools will bring them to a position such as shown in 10 Fig. 5 where the top set is starting to push the smaller and upper eyelet on to the tapered pilot 42 of the bottom set. The arrangement is preferably such that the inwardly flared upper eyelet closely engages 15 the tapered pilot near its outer end and as it is then pushed downwardly along said pilot its flared end is stretched outwardly slightly so that the engagement between the barrel of the upper eyelet and the surface 20 of the pilot 42 is always maintained. This arrangement and the spacing of the barrel of the larger eyelet and the pilot insure the perfect telescoping of the upper and lower eyelets when they are brought 25 into adjacent position such as shown in Fig. 6, and, as soon as the barrel of the larger eyelet supported by the lower set 40 reaches the barrel of the smaller eyelet, it will pass outside the same and be guided through the 30 work by engagement with the outer surface of said barrel. The continued approach of the setting tools will cause the barrel of the smaller eyelet to be upset and preferably to be sharply curled over against the upsetting 35 surface 44 of the bottom set at a level slightly within the level of the outside of the flange of the larger eyelet. By reason of this arrangement, a very smooth surface is secured upon the lower side of the work. 40 In the making of shoes, for example, this lower side will ordinarily be the inside of the upper and it is, therefore, very important that the fasteners when clenched in the work shall present as smooth a surface 45 as possible in order to avoid chafing the foot of the wearer. For the best results, it has been found that the cross-sectional shape of the larger eyelet should be somewhat as shown in Figs. 6 and 7 so that room is provided 50 adjacent to the inner circumference of the flange of the larger eyelet for the roll clenching of the barrel of the smaller eyelet. It should be noted that, regardless of whether or not the barrel of the larger eyelet 55 is clenched upon the work, the clenching of the barrel of the smaller eyelet will serve to secure both fasteners in the work. Preferably, however, the barrel of the larger eyelet is made of such a length that it is upset 60 and clenched against the work by the en-

gagement with the inside of the flange of the smaller eyelet as the same is supported by the annular groove 58 in the top set. In case of variation in the thickness of the work or in case of improper adjustment of the machine, there is no possibility of buckling of the barrel of the smaller eyelet because it is supported from within by the rigid pilot 42 and because it is supported from without by the barrel of the larger eyelet. A perfect opening of uniform size through the coöperating fasteners is, therefore, insured. 70

The feeding of the work to space the eyelets may be accomplished in the usual fashion by lateral movement of the frame 80 10 at the time when the coöperating setting tools are in engagement with the clenched eyelet, this part of the operation being secured similarly to the feeding operation in the machine of the Goddu patent. A hand lever 80 is provided for the purpose of swinging the raceways laterally so that they will not deliver eyelets to the setting tools as, for example, when it is desired to test the operation of the machine or when it is desired 85 only to punch the work.

Having thus described my invention, what I claim as new and desire to secure by Letters Patent of the United States is:

1. In a machine for setting fasteners, co-operative setting tools constructed and arranged to support telescopically proportioned eyelets at opposite sides of the work, means arranged to supply such eyelets to said tools, respectively, and mechanism arranged to move said tools toward each other so as to assemble said eyelets in telescopic relation in the work and clamp one against the other. 95

2. In a machine for setting fasteners, a movable setting tool having a central pilot portion, a movable setting tool having a central bore to receive said pilot portion, a yielding eyelet-supporting spindle in said bore, means arranged to supply to said tools, respectively, the larger and smaller members of telescopically proportioned fasteners, and mechanism arranged to move said tools toward each other so as to carry the fasteners from said supplying means and to assemble them in telescopic relation in the work. 110

3. In a fastener setting machine, coöperating setting tools arranged in axial alignment one above the other to insert eyelets from opposite sides of the work, means for supplying eyelets of one size to the upper setting tool, means for supplying eyelets having a larger sized barrel to the lower setting tool, said upper setting tool being provided with a centrally disposed recess and said lower setting tool being provided with a fixed centrally disposed pilot adapted to thread the barrel of each of the eyelets and to engage closely the barrel of the smaller 115 120 125 130

- eyelet and to enter the recess in the upper setting tool.
4. In a machine for setting fasteners, two coöperative setting tools constructed and arranged to set a barrel member and a reinforcing member of a compound fastener in telescopic relation, and means arranged to supply the barrel member and the reinforcing member to said tools respectively, the tool for the reinforcing member having an annular seat for the latter and having an annular clenching portion the maximum diameter of which is less than the minimum diameter of said seat, said clenching portion being arranged to clench the barrel member against the reinforcing member.
5. In a fastener setting machine, coöperating setting tools arranged in axial alignment to insert fasteners from opposite sides of a piece of work, and means for supplying a barreled fastener and a reinforcing fastener respectively to said setting tools, one of said tools being provided with a centrally disposed tapered pilot for guiding the barrel of the first said fastener and with a raised clenching surface surrounding and closely adjacent to the base of the pilot for clenching said barrel against the flange of said reinforcing fastener, said tool being also provided with an annular seat for engaging and supporting the flange of said reinforcing fastener.
6. In a fastener setting machine, coöperating setting tools arranged in axial alignment one above the other, a raceway constructed and arranged to supply eyelets of one size to the upper tool, means associated with said tool adapted frictionally to support an eyelet delivered thereto by said raceway, another raceway for supplying eyelets of a larger size to the lower tool, and means associated with said lower tool constructed and arranged to project loosely through an eyelet of the larger size and to project through the work to engage tightly the internal surface of the smaller eyelet and thereby to guide the latter into the larger eyelet as the eyelets are moved into telescoping relation.
7. In a machine for setting eyelets in telescopic relation, two movable setting tools raceways arranged to supply telescopically proportioned eyelets to said tools respectively, and mechanism arranged to move said tools so as to carry the eyelets from the raceways into telescopic relation in the work and to clench one against the other.
8. In a machine for setting the complementary members of a compound fastener in telescopic relation, two coöperative setting tools for applying the inner and outer members, respectively, of the fastener, and means for supplying the coöperative members of such a fastener to said tools respectively, the tool for applying the outer member having means constructed and arranged to center the inner member before the latter touches the work.
9. In a fastener setting machine, coöperating setting tools one of which is provided with a rigid projecting pilot and the other of which is provided with a recess adapted to receive said pilot, means for delivering eyelets to each of said setting tools, and means for operating said tools to set said fasteners in telescoping relation with one another and to clench each of them against the other.
10. In a fastener setting machine, coöperating setting tools arranged in axial alignment to operate against opposite sides of a piece of work, means for delivering eyelets of different sizes to the respective tools, and means for operating said tools to insert the eyelets into the work, said tools being constructed and arranged to insure the telescoping of one eyelet within the other and to set the barrel of the innermost eyelet in holding engagement with the flange of the other eyelet.
11. In a machine for setting eyelets in telescopic relation, two coöperative setting tools constructed and arranged to apply the flanges of the eyelets to opposite sides of a piece of work, and means arranged to cause relative movement of said tools such as to assemble the eyelets in telescopic relation in the work and to clench both eyelet barrels.
12. A machine for setting coöperative annular fasteners in telescopic relation, comprising coöperative setting tools one of which is movable toward and from the other, means for supplying telescopic fasteners to said tools respectively, means associated with one of said tools to support the smaller fastener frictionally by engagement with its internal surface, and means for imparting relative movement to said tools to insert the smaller fastener through the other and to clench the smaller fastener against the other.
13. A machine for setting coöperative annular fasteners in telescopic relation, comprising two coöperative setting tools arranged one above the other in coaxial relation, means for supplying to the upper tool a fastener having a barrel and a flange, means arranged to support the fastener in coaxial relation to said tool by frictional engagement with the internal surface of the fastener, the lower tool having a pilot portion arranged to pass through said fastener and formed to fit tightly therein, the lower tool also having a seat to support a fastener adapted to receive the barrel of the upper fastener, and means for moving said tools relatively to insert said barrel through the work and through the lower fastener and to clench the barrel against the lower fastener.

14. A machine for setting coöperative annular fasteners in telescopic relation, comprising two coöperative setting tools arranged in coaxial relation one above the other, the lower tool having means for centering an annular fastener of relatively large internal diameter, the lower tool also having a concentric pilot portion formed and arranged to project loosely through said fastener and through a hole in a piece of work, means for depositing on the upper end of said pilot portion a fastener having a flange and a barrel such as to fit tightly on the pilot portion, and means for relatively moving said tools to assemble the fasteners in telescopic relation on the lower end of said pilot portion and to clench the lower end of said barrel against the lower fastener.

15. A machine for setting annular fasteners in telescopic relation, comprising two coöperative setting tools arranged one above the other in coaxial relation, the lower tool having means for supporting and centering the larger fastener and having means constructed and arranged to center the smaller fastener and to support the latter frictionally, and means for relatively moving said tools to assemble the fasteners in telescopic relation and to clench one against the other.

16. A machine for setting an eyelet and another annular fastener in telescopic relation, comprising two coöperative setting tools one of which has two concentric annular surfaces in different planes, one of said surfaces being arranged to support the outer fastener and the other one of said surfaces being operable to turn back the barrel of the eyelet into the interior of the other fastener and to clench the turned back portion so that it will not project beyond the base of the outer fastener.

17. A machine for setting coöperative annular fasteners, comprising two coöperative setting tools, and means for relatively moving said tools to assemble two fasteners in telescopic relation and to clench one against the other, one of said tools having two portions formed and arranged to support the fasteners in coaxial relation to each other while inserting the smaller fastener into the hole in the larger fastener.

18. A machine for setting flanged eyelets in telescopic relation, comprising two coöperative setting tools one of which has an annular upsetting surface and an annular

ridge or shoulder surrounding said surface and arranged to engage the internal surface of the barrel of the outer eyelet while the upsetting surface is operating on the inner fastener.

19. A machine for setting flanged eyelets in telescopic relation, comprising a work-support, two coöperative setting tools arranged respectively above and below the work-support, means for supplying small-sized eyelets to the upper tool, means for supplying large-sized eyelets to the lower tool, the latter having a pilot portion formed and arranged to center the smaller eyelet before the latter enters the work and to support the smaller eyelet by frictional engagement with the barrel thereof, and means for operating said tools to insert the leading ends of the eyelet barrels into the work and then into telescopic relation one with the other while both eyelets are supported by engagement with the lower tool, said tools being formed and arranged to clench the smaller eyelet against the flanged end of the larger eyelet.

20. In a fastener setting machine, two raceways arranged to deliver the complementary annular parts of a two-part annular fastener at opposite sides of the plane of the work, respectively, and two coöperative setting tools movable toward and from each other and having central parts arranged to pass through the two parts of such fastener in their respective raceways so as to detach them from the raceways, said tools being arranged to apply the detached fastener parts to the work.

21. In a fastener setting machine, raceways arranged to deliver the complementary parts of a two-part fastener at opposite sides of the plane of the work, respectively, upper and lower setting tools having central parts constructed and arranged to enter the two parts of a fastener in the raceways respectively and to detach the fastener parts from the raceways, the central part of the upper tool being effective to support its respective fastener-element, and means for moving said tools toward each other to assemble the two fastener-parts on the central part of the lower tool and to secure them to the work.

In testimony whereof I have signed my name to this specification.

SYLVESTER LEO GOOKIN.

DISCLAIMER.

1,371,364.—*Sylvester Leo Gookin, Boston, Mass. FASTENER-SETTING MACHINE.*

Patent dated March 15, 1921. Disclaimer filed November 21, 1921, by the assignee, *United Shoe Machinery Corporation*.

Presents this disclaimer—

“To said claims 4 and 12 of said patent which are in the following words, to wit:

“4. In a machine for setting fasteners, two coöperative setting tools constructed and arranged to set a barrel member and a reinforcing member of a compound fastener in telescopic relation, and means arranged to supply the barrel member and the reinforcing member to said tools respectively, the tool for the reinforcing member having an annular seat for the latter and having an annular clenching portion the maximum diameter of which is less than the minimum diameter of said seat, said clenching portion being arranged to clench the barrel member against the reinforcing member.

“12. A machine for setting coöperative annular fasteners in telescopic relation, comprising coöperative setting tools one of which is movable toward and from the other, means for supplying telescopic fasteners to said tools respectively, means associated with one of said tools to support the smaller fastener frictionally by engagement with its internal surface, and means for imparting relative movement to said tools to insert the smaller fastener through the other and to clench the smaller fastener against the other.”
